US0D1018762S

(12) **United States Design Patent** (10) Patent No.: **US D1,018,762 S**
(45) Date of Patent: ** Mar. 19, 2024

(54) **RETICLE**

- (71) Applicant: **Crimson Trace Corporation**,
Columbia, MO (US)
- (72) Inventors: **Tim Meissen**, Columbia, MO (US);
William A. Planck, Columbia, MO
(US); **Michael Lindsay**, Columbia, MO
(US); **Brian Steere**, Columbia, MO
(US); **Michael Cottrell**, Ashland, MO
(US); **Ryan Donahue**, Columbia, MO
(US); **Cale Johanning**, Moberly, MO
(US); **Shane Ball**, Columbia, MO (US)
- (73) Assignee: **Crimson Trace Corporation**,
Columbia, MO (US)
- (**) Term: **15 Years**
- (21) Appl. No.: **29/790,979**
- (22) Filed: **Dec. 23, 2021**
- (51) LOC (14) Cl. **22-01**
- (52) U.S. Cl.
USPC **D22/109**; D14/404; D16/130; D16/134;
D16/136; D24/172
- (58) **Field of Classification Search**
USPC D14/404; D16/130, 134, 136; D22/108,
D22/109, 199; D24/172
CPC F41G 3/00; F41G 3/005; F41G 3/02
See application file for complete search history.
